(57) **CLAIM**

The ornamental design for a handheld transaction terminal, as shown and described.

DESCRIPTION

FIG. 1 is a perspective view of a handheld transaction terminal showing our new design;

FIG. 2 is a second perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The elements illustrated by way of broken lines in FIGS. 1, 4, 5 and 6 are for illustrative purposes only and form no part of the claimed design.
